[57] CLAIM

The ornamental design for a pendant, as shown.

DESCRIPTION

FIG. 1 is a front elevational view of a pendant showing one embodiment of my new design, with the cover partially open;

FIG. 2 is a front elevational view thereof with the cover fully closed;

FIG. 3 is a rear elevational view thereof;

FIG. 4 is a top plan view thereof;

FIG. 5 is a bottom plan view thereof;

FIG. 6 is a right side elevational view thereof; and,

FIG. 7 is a left side elevational view thereof.

The broken line showing of Arabic and Roman Dials, in FIG. 1, is for illustrative purposes only and forms no part of the claimed design.
